UNITED STATES PATENT OFFICE

100,563

DESIGN FOR A POCKET FOLDING CAMERA

Clarence P. Hornung, Hempstead Lake, N. Y., and Jesse L. Bernstein, Jersey City, N. J.

Application April 5, 1935, Serial No. 56,234

Term of patent 3½ years

To all whom it may concern:

Be it known that we, Clarence P. Hornung and Jesse L. Bernstein, citizens of the United States, residing respectively at Hempstead Lake, county of Nassau, State of New York, and Jersey City, county of Hudson, State of New Jersey, have invented a new, original, and ornamental Design for a Pocket Folding Camera, of which the following is a specification, reference being had to the accompanying drawing, forming a part thereof.

Fig. 2 is a front perspective view of the same in a closed position.

We claim:

The ornamental design for a pocket folding camera substantially as shown and described.

CLARENCE P. HORNUNG.
JESSE L. BERNSTEIN.
